NOVEL COMPOUNDS AND SYNTHESES

Elkan R. Blout, Belmont, Milton Green, Newton Highlands, Howard G. Rogers, Weston, and Myron S. Simon, Newton Center, Mass., assignors to Polaroid Corporation, Cambridge, Mass., a corporation of Delaware

No Drawing. Filed Mar. 16, 1959, Ser. No. 799,427
3 Claims. (Cl. 260—377)

This invention relates to photography and more particularly to products, compositions and processes for the development of photo-sensitive silver halide elements.

It is one object of the present invention to provide novel processes and compositions for the development of silver halide emulsions, in which colored developing agents are used to develop a latent image.

Another object is to provide novel processes and compositions for the development of silver halide emulsions, in which the novel developing agent is capable of developing a latent image and imparting a reversed or positive colored image of said latent image to a superposed image-receiving material.

Still another object is to provide novel products, processes and compositions suitable for use in preparing monochromatic and multichromatic photographic images.

A further object is to provide novel compounds which are useful as photographic color-providing materials.

Other objects of the invention will in part be obvious and will in part appear hereinafter.

The invention accordingly comprises the processes involving the several steps and the relation and order of one or more of such steps with respect to each of the others, and the products and compositions possessing the features, properties and the relation of elements which are exemplified in the following detailed disclosure, and the scope of the application of which will be indicated in the claims.

The novel photographic developing agents employed in this invention possess the properties of both dye and a developing agent; thus they may be referred to as dye developers. The nature of these dye developers will be described hereinafter.

The photographic processes and compositions disclosed herein are particularly useful in the treatment of a latent image present in a photosensitive element, such as an exposed silver halide emulsion, whereby a positive dye image thereof may be imparted to another element, herein referred to as an image-carrying or image-receiving element.

U.S. Patent No. 2,983,606, issued May 9, 1961, discloses diffusion-transfer reversal processes wherein a photographic negative material such as a photographic element comprising an exposed silver halide emulsion layer containing a latent image, is processed to impart to an image-receiving element a reversed or positive dye image of said latent image by permeating into said emulsion layer a suitable liquid processing composition and bringing said emulsion layer into superposed relationship with an appropriate image-receiving layer. It is an object of this invention to provide additional dye developers suitable for use in such processes.

In carrying out the process of this invention, a photosensitive element containing a silver halide emulsion is exposed and wetted with a liquid processing composition, for example, by immersing, coating, spraying, flowing, etc., in the dark, and the photosensitive element superposed, prior to, during or after wetting, on a sheet-like support element, which may be utilized as an image-receiving element. In a preferred embodiment, the photosensitive element contains a layer of dye developer, and the liquid processing composition is applied to the photosensitive element in a uniform layer as the photosensitive element is brought into superposed position with an image-receiving element. It is also within the scope of

2

this invention to apply the liquid processing composition prior to exposure, in accordance with the disclosure in the copending application of Edwin H. Land, Serial No. 498,672, filed April 1, 1955. The liquid processing composition permeates the emulsion to provide a solution of dye developer substantially uniformly distributed therein. As the latent image is developed, the oxidation product of the dye developer is immobilized or precipitated in exposed areas, thereby providing an imagewise distribution of unoxidized dye developer dissolved in the liquid processing composition. This immobilization is apparently, at least in part, due to a change in the solubility characteristics of the dye developer upon oxidation, and especially as regards its solubility in alkaline solutions. It may also be due, in part, to a tanning effect on the emulsion by the oxidized developing agent and to localized exhaustion of alkali due to development. At least part of this imagewise distribution of unoxidized dye developer is transferred, by imbibition, to a superposed image-receiving layer or element, said transfer substantially excluding oxidized dye developer. Under certain circumstances, the layer of the liquid processing composition may be utilized as the image-receiving layer. The latter element receives a depthwise diffusion, from the emulsion, of unoxidized dye developer without appreciably disturbing the imagewise distribution thereof to provide a reversed or positive, colored image of the developed image. The image-receiving element may contain agents adapted to mordant or otherwise fix the diffused, unoxidized dye developer. If the color of the diffused dye developer is affected by changes in the pH of the image-receiving element, this pH may be adjusted in accordance with well-known techniques to provide a pH affording the desired color. Imbibition periods of approximately one minute have been found to give good results, but this contact period may be adjusted where necessary to compensate for variations in temperature or other conditions. The desired positive image is revealed by stripping the image-receiving element from the photosensitive element at the end of the imbibition period.

The dye developers of this invention may be utilized in the photosensitive element, for example, in, on or behind the silver halide emulsion, or they may be utilized in the image-receiving element or in the liquid processing composition. In a preferred embodiment, a coating or layer of the dye developer is placed behind the silver halide emulsion, i.e., on the side of the emulsion adapted to be located most distant from the photographed subject when the emulsion is exposed and preferably also adapted to be most distant from the image-receiving element when in superposed relationship therewith. Placing the dye developer behind the emulsion layer, as in the preferred embodiment, has the advantage of providing increased contrast in the positive image, and also minimizes any light-filtering action by the colored dye developer. In this preferred embodiment, the layer of dye developer may be applied by using a coating solution containing about 0.5 to 8%, by weight, of the dye developer. Suitable concentrations may be used if the dye developer is utilized as a component of the liquid processing composition, concentrations as low as 0.2% in the liquid processing composition being suitable in certain instances.

The liquid processing composition above referred to comprises at least an aqueous solution of an alkaline compound, for example, diethylamine, sodium hydroxide or sodium carbonate, and may contain the dye developer. In some instances, it may contain a conventional developing agent. If the liquid processing composition is to be applied to the emulsion by being spread thereon, preferably in a relatively thin, uniform layer, it may also include a viscosity-increasing compound constituting film-forming material of the type which, when said composi-

tion is spread and dried, will form a relatively firm and relatively stable film. A preferred film-forming material is a high molecular weight polymer such as a polymeric, water-soluble ether inert to an alkali solution, as, for example, hydroxyethyl cellulose or sodium carboxymethyl cellulose. Other film-forming materials or thickening agents whose ability to increase viscosity is substantially unaffected when left in solution for a long period of time may also be used.

The novel compounds of the present invention comprise anthraquinone dyes characterized in that they contain not less than one and preferably not more than four groups, more preferably not more than two groups, of the formula:

wherein Y and Y', each of which may be the same or different, represent a divalent radical or a covalent bond; R represents hydrogen or a lower alkyl group; and Z represents a benzenoid developing group.

The preferred compounds of the present invention may be represented by the formula:

wherein Y, R, Y', and Z have the same significance as noted in Formula I; and x is an integer from 1 to 4, inclusive.

In a preferred embodiment of Formula II, Z is p-dihydroxyphenyl group; Y' is an ethylene group; Y is a covalent bond; R is hydrogen; and x is 2.

The term "anthraquinone," as used herein, includes both unsubstituted and substituted anthraquinone nuclei. The anthraquinone nucleus may be substituted by various groups, such as hydroxyl; amino; aryl, e.g., phenyl; alkyl, e.g., methyl, ethyl, etc.; cycloalkyl, e.g., cyclohexyl; heterocyclic; aralkyl, e.g., benzyl; substituted amino, e.g., anilino, toluidino, ethylamino; halogen; nitro, etc.

As examples of divalent radicals, signified by the terms "Y" and "Y'" in Formulae I and II and suitable for use in the practice of the present invention, mention may be made of: divalent organic radicals such as alkylene radicals, preferably lower alkylene radicals such as ethylene, isopropylene, etc.; arylene radicals such as phenylene, etc.; aralkylene radicals such as phenethyl, etc.; acyl radicals such as

etc.; and divalent organic radicals which contain both hetero and carbon atoms as constituent components, as for example,

etc.

The novel compounds of the present invention, as noted above, are anthraquinone dye developers which contain at least one benzenoid developing group. As previously noted a preferred silver halide developing group comprises a para-dihydroxyphenyl group. Other suitable developing groups include ortho-dihydroxyphenyl and ortho- and para-amino substituted hydroxyphenyl groups. In general, the developing group comprises a benzenoid developing configuration, that is, an aromatic developing group which forms quinonoid or quinone products upon oxidation. Preferred aromatic developing groups which form quinonoid or quinone oxidation products comprise aryl nuclei selected from the group consisting of benzene and naphthalene nuclei so substituted by at least two groups selected from the group consisting of hydroxyl and amino groups as to be capable of developing an exposed silver halide emulsion.

The term "amino," as used above, is intended to include substituted amino groups, for example, alkylamino and arylamino groups. It will be recognized that the substituents on the amino groups preferably comprise radicals which provide little or no decrease in the silver halide developing function of the amino groups.

One method of preparing the novel dye developers of this invention comprises reacting, preferably in the presence of a suitable halogen acid acceptor, such as for example, quinoline, anhydrous pyridine, etc., a compound of the formula:

wherein Y' and R have the same significance as previously noted; such as for example:

Amino-ethyl-hydroquinone, the preparation of which is disclosed in the copending U.S. application of Milton Green, Serial No. 514,095, filed June 8, 1955;

20 Amino-phenethyl-hydroquinone, the preparation of which is disclosed in U.S. Patent No. 3,019,107, issued January 30, 1962;

Amino-phenethyl-thio-hydroquinone, the preparation of which is disclosed in U.S. Patent No. 3,009,958, issued November 21, 1961;

Amino-phenoxy-hydroquinone, the preparation of which is disclosed in the copending U.S. application of Milton Green and Warren E. Solodar, Serial No. 680,406, filed August 26, 1957;

30 Amino-propyl-amino-hydroquinone, the preparation of which is disclosed in U.S. Patent No. 3,002,997, issued October 3, 1961;

Amino-hydroquinone, amino-phenyl-hydroquinone, and amino-phenyl-sulfonyl-hydroquinone, etc.; which may be prepared by known chemical reactions;

with anthraquinone dye characterized in that it contains not less than one and preferably not more than four groups, more preferably not more than two groups, of the formula:

wherein Y has the same significance as previously noted. Where the anthraquinone dye employed contains more than one acid halide group, the molar ratio of reactants may be varied to provide a condensation reaction between the amine and one or more of the respective acid halide groups.

One method of preparing the compounds of Formula IV is to convert the carboxyl group or groups of an anthraquinone carboxylic acid to the acid halide derivative thereof, for example, to the acid chloride derivative thereof by reaction of said carboxylic group or groups with phosphorous trichloride (PCl_3), phosphorous pentachloride (PCl_5) or thionyl chloride (SOCl_2).

As examples of anthraquinone carboxylic acids suitable for use in the practice of the present invention, mention may be made of:

Anthraquinone-2-carboxylic acid;

1-chloroanthraquinone-2-carboxylic acid;

3-chloroanthraquinone-2-carboxylic acid;

1-nitroanthraquinone-2-carboxylic acid;

1-aminoanthraquinone-2-carboxylic acid;

Anthraquinone-1-carboxylic acid;

Anthraquinone-2,6-dicarboxylic acid;

1,5-dianilino-anthraquinone-2,6-dicarboxylic acid;

1,5-dibromo-anthraquinone-2,6-dicarboxylic acid;

Anthraquinone-1,4-diaminopropionic acid;

3-aminoanthraquinone-2-carboxylic acid;

1-amino-4-bromo-anthraquinone-2-carboxylic acid;

1-amino-4-nitro-anthraquinone-2-carboxylic acid;

1,4-dihydroxyanthraquinone-2-carboxylic acid;

1-nitroanthraquinone-2-carboxylic acid; and

1-anilino-anthraquinone-2-carboxylic acid.

Where an anthraquinone compound has groups other than carboxyl groups which would react during the preparation of the acid chloride, suitable precautions should be taken to avoid undesired side reactions. Thus, where an anthraquinone compound has hydroxyl groups substituted other than on the anthraquinone ring, such groups may be acylated and the protective groups subsequently removed. It has been found that it is unnecessary to protect amino or hydroxyl groups which are substituted in the α -positions of the anthraquinone ring.

The invention will be illustrated in greater detail in conjunction with the following specific examples which set out a representative preparation and photographic utilization of the novel compounds of this invention, which, however, is not limited to the details therein set forth and is intended to be illustrative only.

Example 1

1,5-dianilino-anthraquinone-2,6-dicarboxylic acid (3 g.) is refluxed for about one and one-quarter hours in 25 cc. of thionyl chloride. The solution is then cooled and poured into 100 cc. of dry benzene. A red solid precipitates and is filtered off and dried in vacuo to give 3 g. of the acid chloride. β -Aminoethylhydroquinone hydrobromide (6 g.) in 50 cc. of absolute ethanol is treated with a solution of 1.4 g. of potassium hydroxide in 25 cc. of absolute ethanol. The precipitated salt is filtered and the alcohol removed under vacuum. The residual solid is dissolved in 60 cc. of pyridine. The acid chloride (2.45 g.) prepared above is added, and the solution refluxed under nitrogen for an hour. The reaction mixture is then poured onto ice, acidified with hydrochloric acid, and the solid filtered off. Crystallization from acetic acid gives 2.8 g. of a purple solid melting at approximately 210° C. Analysis of the product based on the structure

1,5-bis-anilino-2,6-bis-(2',5'-dihydroxyphenethylcarbamyl)-anthraquinone, gives a nitrogen value of 7.6% as compared to a calculated value of 7.5%.

Another dye developer within the scope of this invention is

While the preparation of these dye developers has been illustrated starting with an acid chloride derivative of an anthraquinone compound which is a complete anthraquinone dye, other appropriate methods may also be employed. Thus, one may prepare the dye developer of Example 1 by reacting an acid chloride derivative of 1,5-dibromo-anthraquinone-2,6-dicarboxylic acid with β -aminoethylhydroquinone and reacting this product with aniline.

10 Z has been previously defined as a benzenoid developing group. Although, in a preferred embodiment, Z contains a benzene nucleus substituted in the para positions, with respect to each other, by hydroxyl groups, i.e., Z is a hydroquinonyl group, this is intended to be illustrative only. Thus, as previously noted, a silver halide developing function may be imparted to a benzene or naphthalene nucleus by hydroxyl, amino and/or substituted amino groups substituted in the ortho or para positions with respect to each other. It is to be noted also that Z may contain substituents other than those which supply the silver halide developing function so long as such substituents do not destroy the silver halide developing ability; such substituents include alkyl, hydroxyl, amino, halogen, etc. Reference is made to The Theory of the Photographic Process, C. E. K. Mees (1st Ed., 1942), The Macmillan Co., New York, N.Y., p. 342 et seq., for a discussion of the chemical constitution of silver halide developing groups.

20 Where the developing function possessed by Z is supplied by hydroxyl or amino groups, it may be desirable to protect these groups as by acylation, to avoid side reactions or oxidation. Such protective groups are removed, as by hydrolysis, prior to photographic use.

25 One example of a photographic use of the dye developers herein disclosed, and set forth by way of illustration only, is the following:

Example 2

A photosensitive element is prepared by coating a gelatin-coated film base with the following solution:

30 Dye developer prepared in Example 1 _____ g. 0.3
Cellulose acetate hydrogen phthalate _____ g. 0.4
Acetone _____ cc. 8
Methanol _____ cc. 2

45 After this coating has dried, a silver iodobromide emulsion is applied. The photosensitive element is exposed and brought into superposed relationship with an image-receiving element as an aqueous liquid processing composition comprising:

50 Percent
Sodium carboxymethyl cellulose _____ 4.5
Metol _____ 0.1
Sodium hydroxide _____ 2.5

55 is spread between said elements. The image-receiving element comprises a cellulose acetate coated baryta paper which has been coated with a 6% aqueous polyvinyl alcohol solution. After an imbibition period of approximately one minute, the image-receiving element is separated and contains a bluish-magenta positive image of the photographed subject.

60 It will be noted that the liquid processing composition may, and in the above examples does, contain at least one auxiliary or accelerating developer such as p-methoxyaminophenol (Metol); 2,4-diaminophenol (Amidol); benzylaminophenol; or a 3-pyrazolidone, such as 1-phenyl-3-pyrazolidone (Phenidone). The preferred auxiliary developer is 1-phenyl-3-pyrazolidone. This auxiliary developer serves to accelerate and possibly initiate the activation of the dye developer. It is possible that some of the dye developer oxidized in exposed areas may be oxidized by an energy transfer reaction with oxidized auxiliary developer.

65 The dye developers of this invention may be used also in conventional photographic processes, such as tray or

tank development of conventional photosensitive films, plates or papers to obtain black-and-white, monochromatic or toned prints or negatives. By way of example, a developer composition suitable for such use may comprise an aqueous solution of approximately 1 to 2% of the dye developer, 1% sodium hydroxide, 2% sodium sulfite and .05% potassium bromide. After development is completed, any unreacted dye developer is washed out of the photosensitive element, preferably with an alkaline washing medium or other medium in which the unreacted dye developer is soluble. The expression "toned" is used to designate photographic images wherein the silver is retained with the precipitated dye, whereas "monochromatic" is intended to designate dye images free of silver.

It should be noted that the dye developers of this invention are self-sufficient to provide the desired color image and do not depend upon coupling reactions to produce the desired color. They thus provide a complete departure from conventional photographic color processes in which the color is produced by a coupling reaction involving the oxidized developing agent.

The dye developers of this invention are preferably selected with a view to their usefulness in color photography and, in particular, their ability to provide the desired subtractive colors, i.e., magenta, yellow or cyan.

It will be apparent that, by appropriate selection of the image-receiving element from among suitable known opaque and transparent materials, it is possible to obtain either a colored positive reflection print or a colored positive transparency. Likewise, the inventive concepts herein set forth are adaptable for multicolor work by the use of special photographic materials, for example, film materials of the type containing two or more photosensitized elements associated with an appropriate number of image-receiving elements and adapted to be treated with one or more liquid processing compositions, appropriate dye developers suitable to impart the desired subtractive colors being incorporated in the photosensitized elements or in the liquid processing compositions. Examples of such photographic materials are disclosed in U.S. Patent No. 2,647,049 to Edwin H. Land.

The inventive concepts herein set forth are also adaptable for the formation of colored images in accordance with the photographic products and processes described in U.S. Patent No. 2,968,554, issued January 17, 1961, and also the copending application of Edwin H. Land and Howard G. Rogers, Serial No. 565,135, filed February 13, 1956.

In the preceding portions of the specification the expression "color" has been frequently used. This expression is intended to include the use of a plurality of colors to obtain black, as well as the use of a single black dye developer.

5 This application is in part a continuation of our copending U.S. application, Serial No. 521,874, filed July 13, 1955 (now abandoned).

10 Our copending U.S. application, Serial No. 799,426, filed concurrently herewith, claims the photographic utilization of the novel compounds of the present invention, especially in diffusion-transfer reversal processes.

15 Since certain changes may be made in the above products, compositions and processes without departing from the scope of the invention herein involved, it is intended that all matter contained in the above description shall be interpreted as illustrative and not in a limiting sense.

What is claimed is:

20 1. An anthraquinone dye, containing not more than one anthraquinone nucleus, characterized in that it contains, as nuclear substituents, not less than one and not more than two groups of the formula:

25 wherein Y is selected from the group consisting of amino-alkylene groups, wherein said alkylene radicals comprise lower alkylene groups and said amino group is directly substituted on said anthraquinone nucleus, and co-30 valent bonds; Y^I is selected from the group consisting of alkylene, phenylene, and phenalkylene groups, wherein said alkylene radicals comprise lower alkylene groups and said phenylene radical is directly attached to the nitrogen atom of said

35 $\begin{array}{c} \text{H} \\ | \\ -\text{N}- \end{array}$ group, and covalent bonds; and Z is a para-dihydroxy-phenyl group.

40 2. 1,5 - bis - anilino - 2,6 - bis - (2',5' - dihydroxy-phenethylcarbamyl)-anthraquinone.

3. 1,5 - bis - anilino - 2,6 - bis - (2',5' - dihydroxy-phenylcarbamyl)-anthraquinone.
